CARTON

Thomas W. Mahone, Cincinnati, Ohio, assignor
to The Central Carton Company, Cincinnati,
Ohio, a corporation of Ohio

Application October 14, 1937, Serial No. 168,879

5 Claims. (Cl. 229—19)

This invention pertains to cartons or containers formed by folding from blanks or sheets of fiber-board or other material and, more particularly, to a carton peculiarly adapted to hold and retain, for shipment, display and handling, various articles such as soap, bottles and the like which need substantial protection against breakage and disfigurement during transportation and other handling.

10 One of the primary objects of the invention, therefore, is to provide a carton of such construction that the articles it may contain will be secure therein against damage through rough or careless handling.

15 Another of the primary objects is to provide a carton so constructed and arranged that it will employ a minimum amount of material with a minimum amount of waste and a minimum of labor in its manufacture, and one which may be shipped in unfolded or "knocked-down" condition to be folded or "set-up" at its destination or point of use, the construction also being such that the unfolded or "knocked-down" cartons will occupy a minimum amount of shipping space for a 25 given quantity of cartons.

Still another important object is to provide a carton construction of such character that the part thereof actually utilized to receive and to hold the particular commodity packaged there- 30 in may be made from a single blank or sheet of fiber-board or other suitable material, an enclosing tube or cover, if desired or utilized, being composed from another single blank or sheet of the same or some other material. In this connection it should be understood that the part of the carton which is to carry the commodity, as distinguished from the covering tube or jacket, may be utilized alone as a carton or container and without any cover or jacket or with a mere wrapping of "cellophane" or the like.

A further object is to provide a novel carton constructed from a single sheet or blank of fiber-board or other material and in which the sides and ends are re-enforced and, in effect, padded 45 by formation in box-like section to absorb shocks and blows which might otherwise injure the carton contents. In this connection it is to be noted that the preferred construction is such that the carton when folded into its proper form from 50 the blank, is self-sustaining and self-contained so that it is not dependent upon auxiliary means to hold its various sections in proper shape and relation to one another.

And, among other objects, is provision of a 55 carton in the form of a tray or similar receptacle

particularly suitable for the reception and retention for display and other purposes of bars or cakes of soap, the provision of a carton having an article receiving well into which commodities such as cakes or bars of soap whether wrapped or not, may be fitted snugly and frictionally held therein, and the provision of a neat, compact and easily handled carton.

Many other objects as well as the uses and numerous advantages of the invention should be apparent and understood after reading the following description and claims and after viewing the drawings in which:

Fig. 1 is a perspective view of a preferred form of the invention showing the tray or body part of 15 the carton partially withdrawn from the enclosing tube or jacket part.

Fig. 2 is a perspective view of an end portion of tray or body part with some of the sections folded into formed position and other sections in open 20 or unfolded position but ready to be folded.

Fig. 3 is another perspective view of the end portion shown in Fig. 2 but with the end wall folded into shape except for a broken part the better illustrating the construction and folding 25 sequence.

Fig. 4 is a section through an end wall taken along the section line IV—IV of Fig. 1.

Fig. 5 is a developed view of the carton tray or body part or, in other words, a plan view of a 30 sheet or blank as cut and scored ready to be folded into shape, and

Fig. 6 is a small scale view in plan of the blank or sheet from which the tube or jacket part of the carton is to be formed and showing the score 35 lines along which folding is to occur.

Referring first to Figs. 1 and 6 it will be noted that the tube or jacket part generally designated A may be formed from a single blank cut in the shape shown in Fig. 6. Dotted lines 7, 8, 9 and 40 11 indicate score lines or lines along which the folding is to occur and segregate the blank into bottom and top wall sections, 12 and 13, respectively, side wall sections 14 and 15, and a sealing flap 16 upon which glue or other adhesive may 45 be placed for securing the same to the inside face of the side wall section 15. As the blank is illustrated with its outside surface toward the observer, the folding will carry the folded sections away from the observer. The tube or jacket 50 is made in such dimensions as snugly to receive the tray part with a sliding fit therein and may extend for the full length of the tray or terminate beyond or short of the ends thereof as desired. The jacket or tube cover may be shipped 55

in blank form for folding at the place of use or it may be pre-folded at the place of manufacture and then folded down flat at diagonally opposite corners and shipped in that condition.

5 The tray or body part generally designated **B** in Fig. 1, is formed by folding from a blank such as that illustrated in Fig. 5. The blank comprises a bottom wall section **17**, a top wall section **18**, side wall sections **19** and **21**, and a side wall sealing flap **22** upon one face of which an adhesive may be applied for securing the flap to the inside face or surface of side wall section **21**. The sections and flap mentioned are segregated by score or folding lines **23**, **24**, **25** and are intended to be folded away from the observer (viewing Fig. 5) into final shape.

The bottom, top and side wall sections are generally rectangular in shape and the ends of each are provided with integral portions to be utilized 20 in constructing the end walls and in securing the ends in closed position. As previously indicated the carton is provided with box-section side and end walls for protection of the contents and to this end each longitudinal end of the bottom 25 wall section **17** has a projecting portion generally designated **27** adapted to form the end walls and is divided by score lines **28**, **29**, **31** and **32** into segments or parts **33**, **34**, **35** and **36** the purpose and use of which will later appear, and, along 30 the score line **28**, has pre-formed slits **37** which receive fastening tabs as will also appear hereinafter. Segments or parts **34**, **35** and **36** are slightly reduced in their lengths at each end to provide clearance from adjacent parts as will be 35 understood as the description unfolds.

The top wall section **18** has a projecting end wall cover flap or portion **38** at each end segregated from the body of the top section by a score line **39** and each portion **38** carries a pair of tabs 40 **40** segregated by score lines **41** and adapted to be tucked or inserted through the slits **37** when the blank has been folded. Extending for a substantial distance along the longitudinal center line or axis of symmetry of the top section and of a slight 45 width is a pre-formed slot **42** which at each of its opposite ends is flared or widened out into triangular shape as shown at **43** with the bases of the triangles parallel to the score lines **39**. The sides of the triangle lie along lines substantially bisecting the adjacent corners of the top section, in the embodiment shown, and slits **44** extend from the slots **43** outwardly along said bisecting lines for a substantial distance. The slots **42**, **43** and the slits **44** together with longitudinal score lines **45** 50 and transverse score lines **46**, define segments or parts **47** and **48**, the former of which, in turn, are divided by score lines **49** to provide parts **51**. The functions and purposes of these parts will appear later. Each side wall section, **19** and **21**, 55 has a tab flap **52** at each end segregated from its section by a score line **53**. The dimensions of the various sections and parts are so proportioned and chosen as to provide the correspondence and registration thereof necessary to compose the completed carton as illustrated but, of course, these details will be apparent to those skilled in the art.

In folding the blank to form the carton it may be preferable to execute the first folding along 70 score lines **23**, **24**, **25** and **26** to form a tube, the adhesive on flap **22** securing this flap and side wall **21** together. Thereafter it is relatively immaterial whether the box-section end walls or the box-section side walls next be formed. If 75 the end walls be chosen, the segments or parts

33, **34**, **35** and **36** are all folded in the same direction into the shape best illustrated in Fig. 4 and moved into the pre-formed ends of the tube. The tab flaps **52** are then folded in against the outer faces of segments **33** and, thereafter, the end cover flaps **38** are folded thereover and the tabs **40** are inserted or tucked through the slits **37** as best illustrated in Figs. 3 and 4. This completes each end except for the flap segments **48** which may be bent down as illustrated in Figs. 10 2 and 4.

The box-section side walls are formed from the segments or parts **47** and **51** of the top wall **18**, these segments being folded in the same direction along score lines **45** and **49** to the positions 15 shown in Fig. 2. It will be observed that the carton thus constructed provides a well in the top of the tray part into which articles such as cakes of soap may be disposed for display or other purposes, the slight tendency of the box-section side 20 walls and of the flap segments **48** to return to their original positions with respect to the top, serving to an extent to exert sufficient frictional effect upon the articles contained in the well as to secure the articles relatively firmly therein. 25 Of course, the dimensions of the carton will be so chosen as to provide a snug or other proper fit for the articles to be received therein.

The carton is not only strong and secure and able to protect its contents but is attractive in 30 appearance and simple to construct as well as economical and relatively inexpensive. It will be observed that the segments **54** and **55** included between score lines **25**—**45** and **39**—**46**, respectively, provide marginal framing about the well 35 in the top section which lends attractiveness as well as utility to the construction. The widths of segments **55**, preferably are the same as the widths of segments **34** and **36** while the widths of segments **33** and **35** are equal and adapted to 40 bring segment **34** snugly beneath and into supporting contact with the bottom faces of segments **55**. Likewise segments **51** and **54** are substantially equal, preferably, with one another in width so that segments **47** will stand perpendicular to the bottom wall **17** and parallel to the segments **19** and **21**. 45

While I have illustrated and described a preferred embodiment of the invention, it will be appreciated and understood that variations and 50 modifications may be made without departing from the spirit of the invention and the scope of the appended claims.

I claim:

1. A carton comprising, a generally rectangular outer inclosing tube part and a generally rectangular inner enclosed tray part, said tray part being formed by folding from a single sheet of material and including imperforate bottom and side walls, a centrally open top wall, and end walls, the sheet being folded to lap along one side wall, the opening in the top wall being completely bounded by a marginal, unbroken border portion extending in substantially parallel relation to the bottom wall and forming a substantially rectangular framing about the opening, the opposed edges of each one of opposite side parts of said border framing having an integral portion bent downwardly toward and substantially into contact with said bottom wall and thence bent and 60 extending a substantial distance toward the adjacent side wall, the opposed edges of each of the end parts of said border framing having an integral part bent downwardly substantially to said bottom wall, each end wall being formed from a 65

piece integral with the bottom wall and folded along score lines into a box-section fitting beneath and against the bottom of the adjacent of said end parts of the border framing and being substantially coextensive therewith in length and width, tabs integral with each of the opposite ends of each of the side walls and folded over and against the end walls, and an end cover flap integral with each end of the top wall and bent 10 downwardly to cover each end wall, each end cover flap having at least one tab tucked through a slit in the end wall.

2. A carton comprising, a generally rectangular outer inclosing tube part and a generally rectangular inner enclosed tray part, said tray part being formed by folding from a single sheet of material and including imperforate bottom and side walls, a centrally open top wall, and end walls, the sheet being folded to lap along one side wall, 20 the opening in the top wall being completely bounded by a marginal, unbroken border portion extending in substantially parallel relation to the bottom wall and forming a substantially rectangular framing about the opening, the opposed edges of each one of opposite side parts of said border framing having an integral portion bent downwardly toward and substantially into contact with said bottom wall and thence bent and extending a substantial distance toward the adjacent side wall, each end 25 wall being formed from a piece integral with the cent side wall, each end wall being formed from a piece integral with the bottom wall and folded along score lines into a box section fitting beneath and against the bottom of the adjacent of said end parts of the border framing and being substantially coextensive therewith in length and width, tabs integral with each of the opposite ends of each of the side walls and folded over and against the end walls, and an end cover flap integral with each end of the top wall and bent 30 downwardly to cover each end wall, each end cover flap having at least one tab tucked through a slit in the end wall.

3. A carton comprising, a generally rectangular outer inclosing tube part and a generally rectangular inner enclosed tray part, said tray part being formed by folding from a single sheet of material and including imperforate bottom and side walls, a centrally open top wall, and end walls, the opening in the top wall being completely bounded by a border portion extending in substantially parallel relation to the bottom wall and forming a substantially rectangular framing about the opening, the opposed edges of each one of opposite side parts of said border framing having an integral portion bent downwardly toward and substantially into contact with said bottom wall and thence bent and extending a substantial distance toward the adjacent side wall, the op-

posed edges of each of the end parts of said border framing having an integral part bent downwardly substantially to said bottom wall, each end wall being formed from a piece integral with the bottom wall and folded along lines into a box-section fitting beneath and substantially against the bottom of the adjacent of said end parts of the border framing and being substantially coextensive therewith in length and width, and an end cover flap integral with each end of the top wall and bent downwardly to cover each end wall, each end cover flap having at least one tab tucked through a slit in the end wall.

4. A carton comprising, a generally rectangular outer inclosing tube part and a generally rectangular inner enclosed tray part, said tray part being formed by folding from a single sheet of material and including imperforate bottom and side walls, a centrally open top wall, and end walls, the opening in the top wall being completely bounded by a border portion extending in substantially parallel relation to the bottom wall and forming a substantially rectangular framing about the opening, the opposed edges of each one of opposite side parts of said border framing having an integral portion bent downwardly toward and substantially into contact with said bottom wall and thence bent and extending a substantial distance toward the adjacent side wall, each end wall being formed from a piece integral with the bottom wall and folded along lines into a box section fitting beneath and substantially against the bottom of the adjacent of said end parts of the border framing and being substantially coextensive therewith in length and width, and an end cover flap integral with each end of one wall and bent to cover each end wall, each end cover flap having at least one tab tucked into the carton at the adjacent end thereof.

5. A carton comprising, a one piece sheet of material such as fiber board and the like folded to provide a rectangular receptacle having box-section side and end walls, end wall cover flaps extending over the outer faces of the end walls, a substantially closed bottom wall, and a top wall having a generally rectangular opening defined by integrally connected and unbroken marginal edges thereabout, said marginal edges at the sides having downwardly and thence outwardly bent portions forming parts of the said box-section side walls, the bottom wall at the carton ends having projecting portions folded into and forming the box-section end walls, and one of said end cover flaps projecting from each of said marginal edges at the ends of the latter and folded down and secured against the outer face of the adjacent box-section end wall.

THOMAS W. MAHONE.
